UNITED STATES PATENT OFFICE.

ERWIN H. RICHARDS, OF NORWALK, OHIO, ASSIGNOR TO THE MILTON
BRADLEY COMPANY, OF SPRINGFIELD, MASSACHUSETTS.

DEVICE FOR PLAYING GAMES OF SKILL.

SPECIFICATION forming part of Letters Patent No. 448,574, dated March 17, 1891.

Application filed November 20, 1890. Serial No. 371,996. (No model.)

To all whom it may concern:

Be it known that I, ERWIN H. RICHARDS, a citizen of the United States, residing at Norwalk, in the county of Huron and State of Ohio, have invented new and useful Improvements in Devices for Playing Games of Skill, of which the following is a specification.

This invention relates to improved devices for playing a game of skill.

10 The devices consist of a board having parallel rows of depressions or pockets and movable dice or beads for "men."

15 In the accompanying drawings, forming part of this specification, the game devices are illustrated.

Figure 1 is a plan view of the board, showing men disposed thereon as in the course of play. Fig. 2 is a longitudinal section of the board, taken on the line xx , which is through 20 one row of pockets. Fig. 3 is a very much enlarged representation of one of the movable men.

As shown, the board a has four parallel rows 25 of holes or pockets b , eleven in each row, and at each end the board is provided with a receptacle d for containing the captured men in the playing of the game or for containing all the men when the board is in disuse or transportation. A cover is to be provided, 30 as indicated by dotted lines f in Fig. 2. Sixty men are deemed to be a sufficient and desirable number to employ.

The board is placed between the players, as usual, with the longer sides next to them. 35 The row of pockets then nearest each player is considered as such player's "outer row," while the row of pockets next within such outer row is called the player's "inner row." Before beginning the game each player places a single 40 man in each of the pockets of his outer row and two men in each pocket of his inner row, except that the pocket on his extreme left in his inner row is left vacant and the one next to it holds but one man. As indicated by the 45 arrows, all moves in the inner row are from right to left and those in the outer row from left to right. As the players face each other, the moves in the two inner rows are necessarily in opposite directions. The first player 50 chooses any pocket in his inner row which contains more than one man from which to

start his first move, and begins the game by picking up all the men in that pocket and dropping them one by one in each of the consecutive pockets to the left until all the men 55 so picked up have been distributed. If the last counter drops into an occupied pocket, the player continues by picking up all the men in that pocket, including the one dropped, and disposing of them as before. His move 60 must continue in this way until the last man in his hand falls into an empty pocket, and the move may extend around the course into the outer row, or, if of sufficient duration, around again into the inner row, as indicated 65 by the arrows. If this empty pocket into which the last man falls is in the inner rows and has opposite it a pocket in the opponent's inner row containing one or more men, the player captures these men and removes them 70 to his receptacle d , and if there are one or more men in the corresponding opposite pocket of the opponent's outer row they are also taken. Furthermore, he selects another pair of opposite pockets in his opponent's rows 75 from which to remove the men therein contained. In making this choice the player is at liberty to pick out any pair of opposites, whether both are occupied or empty or but one of the pair is occupied. 80

Supposing that A is playing, he may begin from the pocket marked 3, and picking up the men therein he drops them successively into the pockets at the left, the last man dropping into the empty pocket 8. He therefore 85 is entitled to capture the men in his opponent's opposite pockets 5 and 5'. He is also at liberty to select any other pair of his opponent's pockets—as, for instance, 4 and 4'. B then plays. The winner is the one who captures all his opponent's men. 90

Various rules and modifications thereof of course may be adopted, and the devices for playing the game may be modified to a greater or less extent—as, for instance, the number of 95 pockets may be varied or a greater or less number of men may be employed.

What I claim as my invention is—

1. Game devices consisting of a board and a series of movable men, the said board having parallel rows of depressions or pockets, 100 the pockets of one row being opposite those

of the other, and each of the pockets consisting of an opening sufficiently large to receive therein several of said movable men, substantially as and for the purposes set forth.

5 2. Game devices consisting of a board and a series of movable men, the said board having parallel rows of depressions or pockets, the pockets of one row being opposite those of the other and each of said pockets consisting of an opening sufficiently large to receive therein several of said movable men, and receptacle-depressions in said board suitable to contain captured men, substantially as described.

3. Devices for the playing of a game, substantially as described, consisting of a board and a series of movable men, the said board having four parallel rows of depressions or pockets, each of which consists of an opening sufficiently large to receive therein several of 15 said movable men, the pockets of said rows being respectively opposite, substantially as shown.
